UNITED STATES PATENT OFFICE

PAUL C. THOMAS, OF SCRANTON, PENNSYLVANIA

CALENDAR PAD

Application filed January 6, 1931. Serial No. 506,931.

This invention relates to a calendar pad, the general object of the invention being to provide a plurality of envelopes, detachably connected together with each envelope containing data representing a period of one week so that the envelopes form a calendar that can be used by churches, insurance companies, Christmas savings clubs, and the like that require periodical payments of dues so that each weekly amount can be placed in an envelope.

This invention also consists in certain other features of construction and in the combination and arrangement of the several parts, to be hereinafter fully described, illustrated in the accompanying drawings and specifically pointed out in the appended claim.

In describing the invention in detail, reference will be had to the accompanying drawings wherein line characters denote like or corresponding parts throughout the several views, and in which:

Figure 1 is a perspective view showing the invention applied to a picture device.

Figure 2 is a front view of the pad and the frame containing the same.

Figure 3 is a section on line 3-3 of Figure 2.

Figure 4 is a rear view of one of the envelopes.

Figure 5 is a vertical sectional view through the frame.

Figure 6 is a sectional view through a part of the frame.

In these drawings, the numeral 1 indicates the pad formed of fifty two envelopes 2. Each envelope has on its flap side data representing the names of the days of the week as shown at 3 and the numerals 4 representing the dates or days of the month contained in a certain week. The envelope is also provided with data representing the year and the month and any other suitable data. The rear of the envelope contains data indicated

generally at 5 for indicating the amounts

contained in the envelope, the name of the organization which receives the money and the name of the giver or any other suitable data. The ends of the envelope forming the pad may be fastened together by glue or the like but the bottom and top are free to facilitate removal of the envelopes and also the opening of the flaps for the insertion of the dues.

To finish the pad and make it more attractive I provide a frame 6 which surrounds the top and the two sides or ends of the pad and the pad and frame are attached to a base 7 which may be attached to a picture device A as shown in Figure 1.

As shown, the frame 6 is of hollow construction with a straight inner wall and a straight bottom wall and the outer wall curving from the edge of the bottom wall to the top edge of the inner wall and this main frame forms a recess for receiving the pad.

From the foregoing it will be seen that each envelope represents a period of one week dating from Sunday to Saturday with the days of the week thereon and the name of the organization and other data on the back. Each envelope may be removed in consecutive order and the weekly dues or payments inserted and then given to the organization.

It is thought from the foregoing description that the advantages and novel features of the invention will be readily apparent.

It is to be understood that changes may be made in the construction and in the combination and arrangement of the several parts, provided that such changes fall within the scope of the appended claim.

Having thus described my invention, what I claim as new is:

A calendar pad comprising fifty two envelopes each representing a week of a year with data on the flap side of the envelope indicating the year, the month, and the days of the week and the dates and data on the other side of the envelope giving the name of the

organization to which payments are made, etc., a base to which the pad is connected and a frame attached to the base and surrounding the ends and top of the pad said frame being of hollow construction and composed of a flat base wall, a straight inner wall and a curved outer wall connected with the edges of the base and inner walls and the frame forming a three-sided recess for receiving the 10 pad.

In testimony whereof I affix my signature.

PAUL C. THOMAS.
